CLAIM

The ornamental design for a combined truck cab roof
and deflector, as shown and described.

DESCRIPTION

FIG. 1 is a side elevation view of a combined truck
sleeper roof and deflector showing my new design, it
being understood that the broken lines are for illustra-
tive purposes only;

FIG. 2 is a front elevation view thereof;

FIG. 3 is a top plan view thereof; and

FIG. 4 is a rear perspective view thereof.

FIG. 1

FIG. 2

FIG. 3

FIG. 4
